UNITED STATES PATENT OFFICE.

ELIAS GRAHAM, OF LOS ANGELES, CALIFORNIA.

RUBBER-BAND RECEPTACLE.

Application filed October 13, 1924. Serial No. 743,386.

This invention provides an improvement in receptacles for rubber bands.

It is an object of this invention to provide a rubber band receptacle in which the rubber bands are adapted to be placed and through the side walls of which the rubber bands may be readily and quickly drawn.

Another object of this invention is to provide a rubber band receptacle which is rotatably mounted upon a suitable support so that upon rotating the receptacle rubber bands therewithin may have their ends depend through the openings provided in the side walls of the receptacle.

With the foregoing and other objects in view which will be made manifest in the following detailed description and pointed out in the appended claims, reference is had to the accompanying drawings for an illustrative embodiment of the invention, wherein:

Figure 1 is a perspective view of the improved rubber band receptacle.

Fig. 2 is a view similar to Fig. 1 showing the receptacle in the position to be refilled,

Fig. 3 is a top plan view of the receptacle shown in Fig. 1,

Fig. 4 is a vertical section taken substantially on the line 4—4 of Fig. 3,

Fig. 5 is a vertical section taken substantially on the line 5—5 of Fig. 3,

Fig. 6 is a vertical section taken substantially on the line 6—6 of Fig. 3, and

Fig. 7 is a side elevation of a modified form of the receptacle.

Referring to the accompanying drawings wherein similar reference characters designate similar parts throughout, the rubber band receptacle is formed of a tube 10 formed of any suitable foraminous material, which may be of metallic screen of relatively large mesh. It will be noted that the strands of the screen are so arranged that each strand is bent to form a helix, thereby providing diamond-shaped openings 11 in the walls of the tube 10 through which the ends of the rubber bands R may project.

A pair of end closure caps 12 and 13 are removably secured upon the ends of the tube 10 and are maintained in position because of the close fit provided therefor. These closure caps 12 and 13 have grooves 14 and 15 formed therein respectively.

As shown in Figs. 1, 2 and 3 a suitable support is provided which is in the form of a suitable wall strip 16 which may be secured to a wall or similar surface by means

of screws 17, or their equivalent. A ring 18 is formed of wire having its ends twisted about each other, as at 19, and bent to provide oppositely directed feet 20. A pair of staples 21 are driven into the strip 16 and has the feet 20 positioned thereunder. It will be noted that the ring 18 fits within the groove 14 and permits the tube 10 and the closure cap 12 to rotate therein. The ring 18 may pivot with respect to the strip 16, as indicated in Fig. 2.

A similar ring 22 is formed of a single piece of wire having its ends twisted about each other, as at 23, and bent to provide pin portions 24. A pair of apertures 25 are formed in the strip 16 and receive the pin portions 24. A sufficient friction fit is provided for the pin portions 24 within the apertures 25 to maintain the portions 24 therein under normal conditions.

As will readily be appreciated, the tube 10 is swung outwardly as shown in Fig. 2, and the end cap 13 with the ring 22 may be removed and the tube 10 may then be filled with rubber bands R. The cap 13 and the ring 22 are then replaced upon the tube 10 and the pin portions 24 are inserted into the apertures 25. The ends of the rubber bands extend through the openings 11 and may be readily grasped and pulled therethrough. If none of the ends of the rubber bands are extending through the openings 11, the tube 10 may be rotated until some of the ends are in such a position as to extend through the openings 11.

In Fig. 7 there is disclosed a modified form consisting of a tube 10^a formed in the same manner as the tube 10 and provided with movable end caps 12^a and 13^a. The cap 13^a carries a spindle 26 fitting within a bearing 27 provided upon the support 28 which may be secured upon the face of a wall W, or similar surface, by screws 29. The cap 12^a may be removed to fill the tube 10^a with rubber bands; and if none of the ends of the rubber bands extend through the openings in the tube 10^a, the complete receptacle may be quickly rotated and the centrifugal action will cause some of the ends of the rubber bands to be projected through the openings 11^a provided in the tube 10^a.

It will be understood that various changes in the detail of construction may be made without departing from the spirit or scope of the invention as defined by the appended claims.

2
I claim:

1. A rubber band receptacle comprising a tube formed of foraminous material, end closure caps therefor, a support for said receptacle, and means for rotatably mounting said receptacle upon said support.
2. A rubber band receptacle comprising a tube formed of foraminous material, the strands of said foraminous material being arranged to form helixes, end closure caps for said tube, a support for said receptacle, and means for rotatably mounting said receptacle upon said support.
3. A rubber band receptacle comprising a tube formed of foraminous material, end closure caps for said tube, grooves formed in said caps, a support for said receptacle, and rings disposed in said grooves and secured to said support.
4. A rubber band receptacle comprising a tube formed of foraminous material, end closure caps for said tube, grooves formed in said caps, a support for said receptacle,

and rings disposed in said grooves and secured to said support, said tube and closure caps being rotatably mounted in said rings.

5. A rubber band receptacle comprising a tube formed of foraminous material, end closure caps for said tube, grooves formed in said end caps, a support for said receptacle, a ring slidable in the groove of one closure cap and pivoted to said support, and a ring slidable in the groove of the other closure cap and attachably connected to said support.

6. A rubber band receptacle comprising a container adapted to hold rubber bands, said container being provided with walls having a plurality of apertures therethrough, a support for said container, and means for rotatably mounting said container upon said support.

In testimony whereof I have signed my name to this specification.

ELIAS GRAHAM
